UNITED STATES PATENT OFFICE.

JULIUS JUNG, OF STUTTGART, GERMANY.

SCRUBBER.

SPECIFICATION forming part of Letters Patent No. 544,259, dated August 6, 1895.

Application filed September 27, 1894. Serial No. 524,260. (No model.)

To all whom it may concern:

Be it known that I, JULIUS JUNG, of No. 18 Hassenbergstrasse, Stuttgart, in the Kingdom of Württemberg, German Empire, have invented a new and useful Improved Instrument for Cleaning Inlaid or Parquetted Floors, of which the following is a specification, reference being had therein to the accompanying drawings.

10 My invention relates to apparatus for cleaning or brushing floors, and it has for its object to provide an instrument of simple construction by which inlaid flooring or parquetry may be readily and quickly cleaned or brushed 15 without material effort or expenditure of power.

The invention consists in the novel construction and combination of parts hereinafter described and claimed, reference being had 20 to the accompanying drawings, wherein—

Figure 1 is an elevation illustrating the apparatus in use. Fig. 2 is a plan view showing the handle-bar and cleaning implement carried thereby. Fig. 3 is a similar view of 25 the treadle-bar. Fig. 4 is a sectional view showing the cup-like container for metal shavings, and Fig. 5 is a detail view showing the brush which is interchangeable with the metal-shaving container.

30 In the said drawings, the reference-letter A designates the apparatus, which consists of a handle-bar *a*, the lower end of which is forked to form two arms *b*, and at its upper end is provided with a handle *c*. Between the arms *b* of the handle-bar *a* is arranged a spindle *d*, 35 carrying a rotatable roller *e*, and the lower ends of said arms *b* are provided with seats *f*, for the reception of pins *m*, carried by the metal-shavings container *h* and the brush *g*.

40 It is obvious that the said metal-shavings container and brush are interchangeable, the one being substituted for the other, according to the nature of the work to be done. When the container *h* or brush *g* is adjusted in its

place in the arms *b*, the said prongs are adapted 45 to be compressed against the pins *m* to firmly secure the container or brush in place by means of a screw-bolt *k* passing through the arms *b*, and provided at its screw-threaded end with a thumb-nut *i*. The cup-like container is provided with studs or pins *l* on its inner or concave surface for retaining the metal shavings and preventing the same from slipping.

The letter *B* designates a treadle-bar passed 55 between the arms *b* of the handle-bar *a* and rotating freely upon the roller *e*. At one end of the bar *B* is provided a treadle *o*, which is adjustable thereon by means of a securing-pin *p*, which may be passed through any one 60 of a series of perforations *q* in the treadle-bar, as will be obvious. At its opposite end said treadle-bar *B* is provided with a ball *n*.

In use the operation of the apparatus is as follows: The parts being in the described position shown in Fig. 1 of the drawings, in which case the metal-shavings container *h* or the brush *g* may be employed, the operator places his foot upon the treadle *o*, and then by means of the handle *c* quickly moves the 65 70 bar *a*, and consequently the metal-shavings container or brush, backward and forward rapidly, cleaning or brushing the floor.

What I claim is—

An instrument for cleaning or brushing 75 floors, consisting of a handle-bar *a* forked at its lower end to provide arms *b*, a roller *e* carried by said arms, a cleaning or brushing implement secured to said arms, and a treadle-bar passing between the arms *b* and resting 80 substantially as described.

Stuttgart, September 12, 1894.

JULIUS JUNG.
